DESIGN FOR A DRESS

Pauline Fracchia, New York, N. Y.

Application May 7, 1938, Serial No. 77,064

Term of patent 3½ years

To all whom it may concern:

Be it known that I, Pauline Fracchia, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The characteristic feature of my design resides in the combination on the square necked dress disclosed of the specific front yoke in association with the specific shirred shoulders which are closed by slide fasteners as shown.

I claim:

The ornamental design for a dress, substantially as shown, and described.

PAULINE FRACCHIA.
